UNITED STATES PATENT OFFICE

CYRUS HANKINS, OF WASHINGTON, DISTRICT OF COLUMBIA

BRAKE RIGGING FOR RAILWAY CARS

Application filed March 25, 1931. Serial No. 525,239.

My invention relates to railway cars and more particularly to improvements in the brake rigging thereof.

A principal object of the invention is to provide means for connecting the dead lever of the brake rigging to the underframe of the car in such manner that the lever may be free to move angularly with respect to the longitudinal axis of the underframe in substantially all directions to compensate for relative movement between the underframe and the car truck.

A primary feature of the invention consists in providing means for flexibly connecting the dead lever to the underframe of the car involving a member having spaced portions rotatably mounted on the underframe and rigid means having a portion adjacent one end pivotally connected to the dead lever and a portion adjacent the other end positioned between and pivotally connected to the spaced portions of said first-named member.

Another feature of the invention consists in providing rigid means pivotally connected to the upper end of the dead lever and a rotatable member provided with spaced arms carried by the underframe, a portion of said rigid means being interposed between and pivotally connected to the arms of said rotatable member.

A further feature of the invention consists in providing a rotatable member carried by the underframe and rigid means carried by the upper end of the dead lever, pivot pins whose axes are disposed at angles to each other being employed for respectively connecting the rigid means to the rotatable member and the dead lever.

A still further feature of the invention consists in providing a rotatable member carried by the underframe, a pivoted member having spaced arms carried by the dead lever and a rigid member for connecting the rotatable and pivoted members, said rigid member having a portion interposed between the arms of the pivoted member and having oppositely projecting lugs cooperable with said arms.

A still further feature of the invention

consists in providing a U-shaped member rotatably mounted on the underframe and a rigid member for connecting the upper end of the dead lever and the U-shaped member, said rigid member having adjacent one end a portion interposed between the arms of the U-shaped member and portions adjacent the other end overlapping opposite faces of the dead lever.

Other and more specific features of the invention residing in advantageous forms, combinations and relations of parts will hereinafter appear and be pointed out in the claims.

In the drawings illustrating preferred embodiments of the invention:

Figure 1 is a fragmentary, vertical sectional view of a railway car with one form of my invention applied thereto.

Figure 2 is a plan view partly in section of a portion of the construction illustrated in Figure 1.

Figure 3 is an enlarged view partly in section and partly in elevation taken on line 3—3, Figure 1.

Figure 4 is an enlarged sectional view taken on line 4—4, Figure 1.

Figure 5 is a side elevational view, partly in section, of the brackets secured to the underframe of the car and adjacent portions of the dead lever connector.

Figure 6 is a sectional view taken on line 6—6, Figure 5.

Figure 7 is a sectional view taken on line 7—7, Figure 5.

Figure 8 is a plan view of the bracket.

Figure 9 is a side elevational view of one of the dead lever connectors.

Figure 10 is a plan view of the member illustrated in Figure 9.

Figure 11 is an end elevational view of the member illustrated in Figure 9.

Figure 13 is a side elevational view of another one of the dead lever connectors.

Figure 14 is a view similar to Figure 1 illustrating a modified form of the invention.

Figure 15 is a view similar to Figure 2 illustrating the modified form of the invention.

Figure 16 is a view partly in section and partly in elevation taken on line 16-16, Figure 14.

Figure 17 is a sectional view taken on line 5 17-17, Figure 16.

As is well known the conventional brake rigging for railway cars consists of a fluid pressure cylinder rigidly mounted on the underframe of the car and a system of connected rods and levers for transmitting force from the cylinder to brake shoes which cooperate with the wheels of the car. The brake shoes are mounted on brake beams and the latter are pivotally connected to and actuated by 10 the brake levers which, as is known, are inclined at an angle of approximately forty degrees to the vertical. One of these brake levers, namely, the one to which the brake applying force is first transmitted from the 15 brake cylinder, is commonly called the live lever while the other brake lever, namely, the one anchored to some part of the car, is commonly termed the dead lever. As the invention only relates to the means for connecting 20 or anchoring the dead lever to the car only a portion of the brake rigging has been illustrated, namely, the dead lever, designated by the reference numeral 1 and a portion of the push rod, designated by the reference numeral 25 20, which connects the bottom portions of the live and dead levers. The brake beam to which the dead lever is pivotally connected by a pin 3 is also illustrated and it is designated by the reference numeral 4.

30 The means for attaching or anchoring the end of the dead lever to the car underframe illustrated in Figures 1 to 13, inclusive, comprises a tension connector involving a rotatably mounted member carried by the underframe and rigid means pivotally connected at one end to the upper end of the dead lever and pivotally connected at the other end to the rotatably mounted member. The rotatable member, designated by the reference 35 40 45 50 55 60 65 70 75 80 85 90 95 100 105 110 115 120 125 numeral 5, is carried by a bracket 6 rigid with the underframe and is of substantially U-shape having horizontally spaced vertically disposed arms 7 connected by an arcuate portion 8. The bracket 6 may be advantageously formed as an integral casting and is provided with a top portion having longitudinally spaced pad portions 9 each of which is adapted to receive a rivet 10 for rigidly securing the bracket to a bottom flange 11 of one of the center sill members 12 of the underframe. The bracket is also formed with upper and lower jaw members 13 and 14, respectively, spaced below the top portion thereof and integrally connected thereto by web portions 15 and 16, respectively, which extend downwardly from the inner ends of the respective pad portions 9. The web 15 terminates adjacent the lower jaw member 14 and integrally connects the inner ends of both jaws while the web portion 16 terminates ad-

jacent the outer edge of the upper jaw. The web 16 and the portion of the web 15 intermediate the top portion of the bracket and the upper jaw member converge downwardly toward the upper jaw and are connected by a longitudinally extending, preferably centrally disposed, plate portion 17, the upper edge of which is provided with a substantially horizontal rigidifying flange 18 spaced slightly below the pad portions 9. The bracket may be conveniently reinforced by two pairs of oppositely projecting flanges 19 and 20, respectively, the flanges 19 extending between the web 16 and the adjacent pad portion and the flanges 20 extending between the web 15 and the pad portion adjacent the latter. If desired, the flanges 20 may extend, as at 21, beneath the lower jaw member 14 to adjacent the outer edge thereof.

The jaw members of the bracket are preferably connected by a substantially vertical post or member 22 which is adapted to be embraced by the U-shaped rotatable member 5 and serve as an anchorage for the latter. The post is provided with a cylindrically curved surface affording a bearing for the inner surface of the arcuate portion 8 of the rotatable member and both of these surfaces are preferably of substantially the same radii.

By forming the surfaces in this manner it will be observed that an extended bearing area is provided for the rotatable member and in order that the latter will have the same bearing area in substantially all operative positions it may assume, the cylindrical surface of the post is greater than one hundred and eighty degrees in extent. However, since the distance between the arms 7 of the rotatable member is less than twice the radius of the cylindrical surface, the post is formed with a flat side or portion 23 so that the thickness of the post longitudinally of the bracket will be somewhat less than the distance between the arms. With this construction the rotatable member may be easily applied to or removed from the bracket by arranging it at substantially right angles to its normal position. The flat portion of the post is preferably recessed as at 24 so as to reduce the cross sectional area of the post and thereby minimize the possibility of shrinkage cracks during the casting operation of the bracket. To eliminate the necessity of machining the cooperating faces of the cylindrical portion of the post and the arcuate portion of the rotatable member and yet to insure bearing contact at vertically spaced points between these surfaces and preferably at points adjacent the upper and lower edges of the rotatable member, the arcuate portion of the latter is preferably cored as at 25.

The rigid means, heretofore referred to, of the tension connector is preferably formed by two members 26 and 27, respectively. The

member 26 may be advantageously of U-shape having spaced arms 28 disposed in planes substantially parallel with the plane of normal operation of the dead lever. The arms 5 are spaced a sufficient distance apart to receive the upper end of the lever and are pivotally connected thereto by a pin 29, the pivotal axis of which is substantially perpendicular to the plane of normal operation of the lever. 10 In order that the arms and lever may be connected in various positions of adjustment to take up slack in the brake rigging, the arms are provided with a plurality of pairs of registering apertures 30, any pair of which is 15 adapted to receive the connecting pin 29. The other member, 27, of the rigid means is of substantially I-shape in cross section and is formed with angularly disposed end portions 31 and 32. The end portion 31 is substantially vertical and is interposed between the arms 7 of the rotatable member 5, being pivotally connected thereto by a pin 33 whose axis is substantially horizontal. The portion 20 32 is disposed in a plane substantially parallel with the plane of the dead lever and is interposed between the arms 28 of the member 26, being connected to the latter by a pin 34. The portion 32 of the member 27 is integrally formed with laterally extending oppositely 25 projecting lugs 35, one of which is disposed in over-lapping relation to the lower edge of one of the arms of member 26 and the other of which is disposed in overlapping relation to the upper edge of the other arm thereof. 30 It will thus be observed that the members 26 and 27 are immovably connected, the pin 34 serving to prevent relative longitudinal movement thereof and the lugs 35, together with pin 34, serving to prevent relative angular 35 movement. 40

From the foregoing it will be observed that the rigid means is connected at one end by the pivot pin 29 to the dead lever and is connected at the other end by the pivot pin 45 33 to the rotatable member and the axes of 45 these pins are disposed at angles to each other. Moreover, the axis of the rotatable member is substantially vertical and at right angles to the axis of the pivot pin 33. The rigid 50 means is therefore pivotally connected to the dead lever and universally connected to the bracket. Thus the lever is connected to the underframe of the car in such manner that it may move angularly with respect to the 55 longitudinal axis of the underframe in substantially all directions to compensate for relative movement between the car truck and the car body.

In the form of the invention illustrated in 60 Figures 14 to 17, inclusive, the tension connector comprises a rotatable member 36 and a rigid member 37. The rotatable member is mounted upon a bracket 38 rigid with the underframe and is preferably of U-shape 65 having spaced arms 39. The bracket 38 may

advantageously be formed as an integral casting having a top portion 40 for attachment by rivets 41 to the bottom flange 11 of the center sill 12 and a downwardly and outwardly extending box-shaped portion 42. 70 The upper end of the box portion is preferably open so that the bracket may be conveniently cast and the top portion 40 of the latter may be conveniently reinforced along its outer marginal edge by substantially vertical gusset-shaped flanges 43. 75

Projecting downwardly and outwardly from the lower portion of the bracket are spaced jaws 44 which are preferably disposed in planes perpendicular to the plane of normal operation of the dead lever 1. The jaws are provided with registering apertures for receiving a pin 45 for connecting the rotatable member 36 to the bracket. The longitudinal axis of the pin and therefore the axis of rotation of the member 36 is preferably parallel with the plane of normal operation of the dead lever. 80

The rigid member 37 of the tension connector is provided adjacent one end with spaced arms 46 between which the upper end of the dead lever is adapted to be disposed and with a portion 47 adjacent its other end adapted to be interposed between the arms 39 of the rotatable member. The rigid member may be conveniently formed from two similarly shaped members which may be connected together by a rivet 48 so as to provide the spaced arms 46 and the portion 47. Pivot pins 49 and 50 whose axes are substantially normal to the plane of operation of the dead lever are preferably employed for respectively connecting the rigid member to the dead lever and rotatable member. The arms 46 of the rigid member are preferably formed with a plurality of pairs of apertures 51 for receiving the pin 49 so that the rigid member and dead lever may be connected in various positions of adjustment to take up slack in the brake rigging. 95

From the foregoing it will be observed that the rigid member 36 is universally connected to the bracket 38 by the rotatable member 36 and is pivotally connected to the dead lever. Thus the lever is capable of moving angularly with respect to the longitudinal axis of the underframe in substantially all directions to compensate for relative movement between the car truck and the car body. 100

I claim:

1. In a railway car brake rigging, the combination with the underframe of a car and a truck swiveled thereto, of a dead lever carried by the truck, and means connecting the upper end of the dead lever to the underframe adapted to permit the lever to move angularly with respect to the longitudinal axis of the underframe in substantially all directions to compensate for relative movement between the underframe and truck, 115 120 125 130

said means involving a member having spaced portions rotatably mounted on the underframe, and rigid means having a portion adjacent one end pivotally connected to the lever and a portion adjacent the other end interposed between and pivotally connected to the spaced portions of said first-named member.

2. In a railway car brake rigging, the combination with the underframe of a car and a truck swiveled thereto, of a dead lever carried by the truck, and means connecting the upper end of the dead lever to the underframe adapted to permit the lever to move angularly with respect to the longitudinal axis of the underframe in substantially all directions to compensate for relative movement between the underframe and truck, said means involving a member rotatably mounted on the underframe and provided with spaced portions, rigid means carried by the dead lever, and pivot pins for respectively connecting the rigid means to the dead lever and rotatable member, the portion of the rigid means connected to the rotatable member being interposed between the spaced portions of the latter.

3. In a railway car brake rigging, the combination with the underframe of a car, of a dead lever, and means for connecting the upper end of the dead lever to the underframe to permit the lever to move angularly with respect to the longitudinal axis of the underframe in substantially all directions, said means involving a rotatable member provided with spaced portions carried by the underframe, and rigid means having spaced portions adjacent one end pivotally connected to and overlapping opposite faces of the dead lever and a portion adjacent the other end interposed between and pivotally connected to the spaced portions of the rotatable member.

4. In a railway car brake rigging, the combination with the underframe of a car and a truck swiveled thereto, of a dead lever carried by the truck, and mechanism connecting the upper end of the dead lever to the underframe adapted to permit movement of the dead lever in substantially all directions relative to the underframe to compensate for relative movement between the latter and the truck, said mechanism involving rigid means pivotally connected to the upper end of the dead lever, and a rotatable member provided with spaced arms carried by the underframe, a portion of said rigid means being interposed between the arms of said rotatable member and being pivotally connected thereto.

5. In a railway car brake rigging, the combination with the underframe of a car and a truck swiveled thereto, of a dead lever carried by the truck, and means connecting the upper end of the dead lever to the under-

frame adapted to permit movement of the dead lever in a plurality of directions relative to the underframe to compensate for relative movement between the latter and the truck, said means involving a substantially U-shaped member rotatably mounted on the underframe, rigid means carried by the upper end of the dead lever, and pivot pins for respectively connecting the rigid means to the dead lever and U-shaped member, the portion of the rigid means connected to the U-shaped member being interposed between the arms of the latter.

6. In a railway car brake rigging, the combination with the underframe of a car and a truck swiveled thereto, of a dead lever carried by the truck, and means connecting the upper end of the dead lever to the underframe adapted to permit movement of the dead lever in a plurality of directions relative to the underframe to compensate for relative movement between the latter and the truck, said means involving a rotatable member carried by the underframe, rigid means carried by the upper end of the dead lever, and pivot pins for respectively connecting the rigid means to said rotatable member and the dead lever, the axes of said pins being disposed at angles to each other.

7. In a railway car brake rigging, the combination with the underframe of a car and a truck swiveled thereto, of a dead lever carried by the truck, and means connecting the upper end of the dead lever to the underframe adapted to permit movement of the dead lever in a plurality of directions relative to the underframe to compensate for relative movement between the latter and the truck, said means involving a rotatable member carried by the underframe, rigid means carried by the upper end of the dead lever, and pivot pins for respectively connecting the rigid means to said rotatable member and the dead lever, the axis of the pin connecting said means and dead lever being substantially perpendicular to the plane of normal operation of the latter, and the axis of the other of said pins being disposed at an angle to the said plane of operation of the lever.

8. In a railway car brake rigging, the combination with the underframe of a car and a truck swiveled thereto, of a dead lever carried by the truck, and means connecting the upper end of the dead lever to the underframe adapted to permit movement of the dead lever in a plurality of directions relative to the underframe to compensate for relative movement between the latter and the truck, said means involving a rotatable member carried by the underframe, rigid means carried by the upper end of the dead lever, and pivot pins for respectively connecting the rigid means to said rotatable member and the dead lever, the axis of the pin connecting the rigid means and lever be-

ing substantially perpendicular to the plane of normal operation of the latter and the axis of the pin connecting the rigid means and the rotatable member being substantially 5 horizontal.

9. In a railway car brake rigging, the combination with the underframe of a car, of a dead lever, a rotatable member carried by the underframe, rigid means carried by the 10 upper end of the dead lever, and pivot pins for respectively connecting the rigid means to said rotatable member and the dead lever, the axis of rotation of said rotatable member being substantially vertical and the axes of 15 said pins being disposed at an angle to each other and to the said axis of rotation.

10. In a railway car brake rigging, the combination with the underframe of a car, of a dead lever, a rotatable member carried 20 by the underframe, rigid means carried by the upper end of the dead lever, and pivot pins for respectively connecting the rigid means to said rotatable member and the dead lever, the axis of rotation of said rotatable member 25 being substantially vertical, the axis of the pin connecting the rigid means and dead lever being substantially perpendicular to the plane of normal operation of the latter and the axis of the pin connecting the rigid means 30 and the rotatable member being substantially horizontal.

11. In a railway car brake rigging, the combination with the underframe of a car, of a dead lever, of a rotatable member provided 35 with horizontally spaced portions carried by the underframe, the axis of rotation of said member being substantially vertical, rigid means carried by the upper end of the dead lever, and pivot pins for respectively 40 connecting said rigid means to the upper end of the dead lever and to the rotatable member, the portion of the rigid means connected to the rotatable member being interposed between the spaced portions of the latter and 45 the axes of said pivot pins being disposed at angles to each other.

12. In a railway car brake rigging, the combination with the underframe of a car, of a dead lever, a rotatable member provided 50 with horizontally spaced portions carried by the underframe, the axis of rotation of said member being substantially vertical, rigid means carried by the upper end of the dead lever, a pin whose axis is substantially perpendicular to the normal plane of operation 55 of the dead lever connecting said rigid means to the upper end of the lever, and a pivot pin whose axis is substantially horizontal connecting said rigid means to the rotatable 60 member, the portion of the rigid means connected to the rotatable member being interposed between the spaced portions of the latter.

13. In a railway car brake rigging, the combination with the underframe of a car,

of a dead lever, and means for connecting the upper end of the dead lever to the underframe, said means involving a rotatable member carried by the underframe and rigid means having a portion adjacent one end 70 pivotally connected to the dead lever and a portion adjacent the other end pivotally connected to the rotatable member, the portion of said means connected to the dead lever being disposed in a plane substantially parallel to the plane of normal operation of the lever and the portion of said means connected to the rotatable member being disposed in a substantially vertical plane. 75

14. In a railway car brake rigging, the combination with the underframe of a car and a truck swiveled thereto, of a dead lever, carried by the truck, and means connecting the upper end of the dead lever to the underframe adapted to permit movement of the dead lever in a plurality of directions relative to the underframe to compensate for relative movement between the latter and the truck, said means involving a rotatable member provided with horizontally spaced 80 portions carried by the underframe, and rigid means having spaced arms overlapping opposite faces of the dead lever and pivotally connected thereto, said rigid 85 means also having a portion interposed between and pivotally connected to said spaced portions of the rotatable member. 90

15. In a railway car brake rigging, the combination with the underframe of a car and a truck swiveled thereto, of a dead lever carried by the truck, and means connecting the upper end of the dead lever to the underframe adapted to permit movement of the dead lever in a plurality of directions relative to the underframe to compensate for relative movement between the latter and the truck, said means involving a bracket rigid with the underframe, a member carried by the bracket, means integral with the bracket for pivotally associating said member with the latter, and rigid means pivotally connected at one end to the dead lever and pivotally connected at the other end to said member. 100

16. In a railway car brake rigging, the combination with the underframe of a car, of a dead lever, a bracket rigid with the underframe, said bracket being provided with spaced portions and with means integrally connecting said portions, a rotatable U-shaped member interposed between said spaced portions of the bracket and embracing said integral connecting means, and rigid means having a portion adjacent one end pivotally connected to the upper end of the dead lever and a portion adjacent the other end interposed between and pivotally connected to the arms of the said U-shaped member. 115

17. In a railway car brake rigging, the

- combination with the underframe of a car, of a dead lever, a bracket rigid with the underframe, and means for movably connecting the upper end of the dead lever to said bracket, said bracket involving a top portion for attachment to the underframe, upper and lower jaw members disposed below the latter, and a plurality of web portions, one of said web portions integrally connecting the inner ends of both of said jaw members to the said top portion and the other of said web portions integrally connecting the outer end of the upper jaw member to the top portion.
18. In a railway car brake rigging, the combination with the underframe of a car, of a dead lever, a bracket rigid with the underframe, and means for movably connecting the upper end of the dead lever to said bracket, said bracket involving a top portion for attachment to the underframe, upper and lower jaw members disposed below the latter, and a plurality of web portions extending downwardly from said top portion, one of said web portions integrally connecting the inner ends of both of said jaws to the said top portion and the other of said web portions integrally connecting the outer end of the upper jaw to the top portion, said web portions being integrally formed with oppositely projecting rigidifying flanges.
19. In a railway car brake rigging, the combination with the underframe of a car, of a dead lever, a bracket rigid with the underframe, and means for movably connecting the upper end of the dead lever to said bracket, said bracket involving a top portion for attachment to the underframe, upper and lower jaw members disposed below the latter, downwardly extending web portions integrally connecting said jaw members to the top portion, one of said web portions being disposed adjacent the inner ends of the jaw members and terminating adjacent the lower jaw and the other of said web portions terminating adjacent the outer end of the upper jaw, and means formed integrally with said upper jaw for connecting both of said web portions above the latter.
20. In a railway car brake rigging, the combination with the underframe of a car, of a dead lever, a bracket rigid with the underframe, and means for movably connecting the upper end of the dead lever to said bracket, said bracket involving spaced pad portions for attachment to the underframe, upper and lower jaw members disposed below the latter, and a plurality of web portions extending downwardly from the inner edges of said pad portions, one of said web portions integrally connecting the inner ends of both jaws to one of the pad portions and the other of said web portions integrally connecting the outer end of the upper jaw member to the top portion.
21. In a railway car brake rigging, the combination with the underframe of a car, of a dead lever, a bracket rigid with the underframe, and means for movably connecting the upper end of the dead lever to said bracket, said bracket involving spaced pad portions for attachment to the underframe, upper and lower jaw members disposed below the latter, a plurality of web portions extending downwardly from adjacent the inner edges of said pad portions, and a plate portion integrally connecting said web portions above the upper jaw member, one of said web portions integrally connecting the inner ends of both of said jaws to one of said pad portions and the other of said web portions integrally connecting the outer end of the upper jaw to the other of said pad portions.
22. In a railway car brake rigging, the combination with the underframe of a car, of a dead lever, and means for movably connecting the upper end of the dead lever to the underframe, said means involving two relatively immovable members, one of said members being pivotally connected to the dead lever and having spaced arms, the other of said members having a portion interposed between said arms, said interposed portion having oppositely extending laterally projecting lugs, one of said lugs being disposed in overlapping relation to one edge of one of said arms and the other of said lugs being disposed in overlapping relation to the opposite edge of the other of said arms.
23. In a railway car brake rigging, the combination with the underframe of a car, of a dead lever, and means for movably connecting the upper end of the dead lever to the underframe, said means comprising a pivoted member having spaced arms for receiving the upper end of the dead lever, a pin connecting said arms and lever, a rigid member movably associated with the underframe, said rigid member having a portion interposed between the arms of said pivoted member, and a pin connecting the rigid and pivoted members, the interposed portion of said rigid member having oppositely extending laterally projecting lugs, one of said lugs being arranged in overlapping relation to one edge of one of said arms and the other of said lugs being arranged in overlapping relation to the opposite edge of the other of said arms.
24. In a railway car brake rigging, the combination with the underframe of a car, of a dead lever, a bracket rigid with the underframe, means connecting the upper end of the dead lever to the bracket, said means involving a movably mounted member carried by the bracket and rigid means connecting

the upper end of the dead lever to said movable member, said rigid means comprising two relatively immovable members, one of said members having spaced arms, the upper 5 end of the dead lever being interposed between said arms and pivotally connected thereto, the other of said members being pivotally connected at one end to said movable member and having a portion adjacent its 10 other end interposed between said arms, said interposed portion being provided with oppositely extending laterally projecting lugs, one of said lugs being arranged in overlapping relation to one edge of one of said 15 arms and the other of said lugs being arranged in overlapping relation to the opposite edge of the other of said arms, and a pin connecting said interposed portion and said arms.

20 25. In a railway car brake rigging, the combination with the underframe of a car, of a dead lever, a bracket rigid with the underframe, a movable member having spaced arms carried by said bracket, a pivoted member having spaced arms carried by the upper end of the dead lever, and a rigid member connecting said movable member and said pivoted member, said rigid member having a portion interposed between and 25 pivotally connected to the arms of said movable member, said rigid member also having a portion interposed between the arms of said pivoted member, said last-named portion of the rigid member being provided with 30 oppositely projecting lugs, one of said lugs being arranged in overlapping relation to one edge of one of the arms of the rigid member and the other of said lugs being arranged in overlapping relation to the opposite edge of the other of said arms of the rigid member.

26. In a railway car brake rigging, the combination with the underframe of a car, of a dead lever, a bracket rigid with the 45 underframe, a movable member having spaced arms carried by said bracket, a pivoted member having spaced arms carried by the upper end of the dead lever, a pin whose axis is substantially perpendicular to the plane of normal operation of the lever pivotally connecting said pivoted member and dead lever, a rigid member respectively having portions interposed between the arms of the movable member and the pivoted member, a pin whose axis is substantially horizontal pivotally connecting said rigid and movable members, the portion of the rigid member interposed between the arms of the 50 pivoted member having oppositely projecting lugs, one of said lugs being arranged in overlapping relation to one edge of one of said arms and the other of said lugs being arranged in overlapping relation to the opposite edge of the other of said arms, and a

pin connecting said rigid and pivoted members.

27. In a railway car brake rigging, the combination with the underframe of a car, of a dead lever, a bracket rigid with the underframe, a U-shaped member having spaced arms movably mounted on the bracket, and a rigid member connecting the upper end of the dead lever and the U-shaped member, said rigid member having a portion adjacent one end interposed between and pivotally connecting to the arms of the U-shaped member and having spaced portions adjacent the other end overlapping opposite faces of the lever and pivotally connected thereto.

28. In a railway car brake rigging, the combination with the underframe of a car, of a dead lever, a bracket rigid with the underframe, a rotatable U-shaped member having spaced arms movably mounted on said bracket, the axis of rotation of said member being inclined with respect to the vertical, and a rigid member connecting the upper end of the dead lever and said rotatable member, said rigid member having a portion adjacent one end pivotally connected to the lever and a portion adjacent the other end interposed between and pivotally connected to the arms of the rotatable member.

29. In a railway car brake rigging, the combination with the underframe of a car, of a dead lever, a bracket rigid with the underframe, a rotatable U-shaped member having spaced arms movably mounted on said bracket, the axis of rotation of said member being inclined with respect to the vertical, a rigid member interposed between the upper end of the dead lever and the rotatable member, and pivot pins for respectively connecting said rigid member to the dead lever and rotatable member, the axes of said pins being substantially perpendicular to the plane of normal operation of the dead lever and the portion of the rigid member connected to the U-shaped member being interposed between the arms of the latter.

30. In a railway car brake rigging, the combination with the underframe of a car, of a dead lever, a bracket rigid with the underframe, said bracket having downwardly inclined jaws, a member rotatably mounted on said bracket and having a portion interposed between said jaws, and rigid means pivotally connected at one end to the dead lever and pivotally connected at the other end to the rotatable member, the pivotal axis of said rotatable member being substantially parallel with the plane of normal operation of the dead lever.

31. In a railway car brake rigging, the combination with the underframe of a car, of a dead lever, a bracket rigid with the underframe, said bracket having a box-shaped portion and spaced jaws extending downwardly therefrom in an inclined direc-
